UNITED STATES PATENT OFFICE

ROBERT T. WILLIAMS, OF QUINCY, ILLINOIS, ASSIGNOR TO H. M. SHEER COMPANY,
OF QUINCY, ILLINOIS, A CORPORATION OF ILLINOIS

OIL CONTROL

Application filed October 27, 1927. Serial No. 229,137.

This invention relates to an improvement in oil controls.

The object of the invention is to provide an oil control for oil burners which may be placed in the center of the latter so as to effectively control the flow of oil to the burner and to maintain approximately the same oil level therein, regardless of any deviation or variation in the position of the burner sup-

10 port.

Oil burners of this character are devised particularly for heating chicken brooders and it very often happens that the floor of a brooder will sag considerably between the 15 burner and oil tank or source of supply, causing a variation in the oil level maintained in the burner often to such an extent as to overflow the burner bowl and create a fire in the brooder itself, which often de- 20 stroys the latter and causes considerable other damage.

This sagging of the floor also has a tendency to tilt the burner to one side to such an extent that the oil very often overflows 25 one side of the burner while being drained from the other. Heretofore, it has been customary to mount an oil control at a point remote from the burner to such an extent that it could not very effectively take care 30 of these deviations in the position of the oil burner, and it could not effectively prevent an overflowing of the oil, but this is accomplished by the oil control embodied in this invention.

35 Whenever the oil control or float chamber therefor is mounted on the outside of the burner bowl, it would not maintain the proper oil level in the burner, regardless of the tilting of the burner in any direction.

40 This invention provides for locating the float chamber approximately at the center of the burner bowl, in which position it maintains the proper oil level in the bowl approximately at all times, regardless of 45 any substantial deviation in the direction in which the oil burner may be tilted. The same oil level is maintained within the float chamber, as in the burner bowl, and since the former is carried by the same support 50 which carries the burner bowl, the two will

be tilted together, and if the burner is tilted in any direction, the rise in the oil level in the burner will also raise the level in the float chamber, which will thereby tend to cut off the flow of oil sufficiently to lower 55 the oil level in the burner and preventing an overflowing of the burner bowl, likewise preventing any destruction or fire within the brooder.

Suitable valve mechanism and associate 60 construction is connected with the float chamber and float for regulating the flow of oil to the burner bowl and this also provides not only the float control for the oil but also a manual control for regulating the 65 oil level in both the burner and float chamber.

In the accompanying drawings:—

Fig. 1 is a perspective view of the complete burner; 70

Fig. 2 is a vertical sectional view therethrough; and

Fig. 3 is a detail plan view of a portion of the burner bowl and float chamber.

The numeral 1 designates the support for 75 the entire burner and float chamber, upon which is mounted an elbow 2 connected by means of a suitable pipe 3 with a source of oil supply or tank (not shown). Extending upwardly from the elbow 2 is a nipple 4, 80 in the upper end of which a valve seat 5 is formed for a purpose hereinafter described. A T 6 is mounted on the nipple 4, one end of which carries a coupling 7 which, in turn, supports a casting 8 in which the lower end of the float chamber 9 is secured, an opening being provided through the bottom of the float chamber 9, the casting 8 and coupling 7 into the T 6, as clearly shown

85 in Fig. 2. A cover sleeve 10 fits over the float chamber 9 so as to cover the latter. Mounted within the float chamber 9 is a float 11 of suitable construction mounted on a valve stem 12, having its upward movement regulated by the nut 13, screwed onto the valve stem. The valve stem extends

90 through the bottom of the float chamber 9, the casting 8, coupling 7, T 6 and nipple 4, and is provided with a needle valve 14 95 formed on the lower end thereof in position 100

to engage the valve seat 5 in the upper end of the nipple 4 for regulating the flow of oil from the pipe 3 and elbow 2 into the T 6.

The casting 8 has arms 15 extending laterally therefrom, as shown in Fig. 1, upon the outer ends of which the burner bowl 16 is supported by means of the small tubes 17 which communicate with the burner bowl 16 and arms 15. The casting 8 has an oil chamber 18 therein, as shown in Fig. 2, which communicates through the arms 15 and tubes 17 with the channel of the burner bowl 16 on opposite sides of the latter, so as to deliver oil to the burner bowl.

A union 19 screws into the side of the T 6 and is provided with a valve seat 20 in the inner end thereof for receiving the needle valve 21, which is regulated by the shaft 22 extending to a hand wheel 23, shown in Fig. 1, and it also carries a pointer 24 for indicating the extent of movement of the shaft and valve 21.

Sleeved over the union 19 and butting against the outer end of the T 6 is a hollow bushing 25 communicating with the interior of the union 19 and T 6 through the lateral openings 26. This hollow bushing 25 also communicates at its upper side with the chamber 18 in the casting 8 through a tube 27, also shown in Fig. 2. The burner bowl 16 may be provided with screens 28 and 29.

In the operation of the burner, the oil passes from the tube 3 which leads to any suitable source of oil supply into the elbow 2 and through the nipple 4 about the valve 14 into the T 6. The oil passes from the T 6 in two directions, up through the coupling 7, casting 8 and into the oil chamber 9 bearing up the float 11 therein, which through the medium of the valve stem 12 and valve 14 regulates the passage of oil through the valve seat 5 into the T 6. The oil also flows from the T 6 through the valve seat 20 and openings 26 into the hollow bushing 25, from where it passes through the tube 27 into the oil chamber 18, which, in turn, directs it laterally in two directions through the arms 15 and tubes 17 into the burner bowl 16.

As it is consumed in the burner bowl, the float 11 will gradually maintain the valve 14 slightly open, allowing a continual flow of oil into the float chamber or burner bowl. The passage of the oil to the burner bowl is also regulated by means of the manually controlled valve 21.

As well understood, in burners of this character a constant oil level is maintained in the float chamber as well as in the burner bowl, this oil level being the same in both. Since the oil in the burner bowl is maintained at the same level as in the float chamber, it is desirable that these shall be as

nearly as possible on the same level, but where the float chamber is placed externally of the burner bowl, as is the usual custom, this has been virtually impossible, and it has also been impossible with any degree of accuracy to obtain anything like a constant level of oil in both the float chamber and burner bowl in the event that the latter should tilt in any direction.

It will be apparent that a tilting of the burner bowl also causes a tilting of the float chamber, but if this should be in the opposite direction from the float chamber it will be evident that the same oil level in the latter will cause an overflowing of the burner bowl, which often results in very serious damages and injury, with very often the destruction of the brooder.

By placing the float chamber in the center or middle of the round burner bowl, this is eliminated to a very high degree and to an extent not heretofore attained. It will be evident that a tilting of the burner bowl in any direction will cause a corresponding tilting of the float chamber, and by reason of its location in the center of the burner bowl, there will be substantially no difference in the relative positions of the two and the oil levels maintained therein.

I claim:—

1. In an oil control for heaters, the combination of a support, a nipple mounted thereon and communicating with a source of oil supply, said nipple having a valve seat formed therein, a T communicating with the nipple through the valve seat, a casting mounted upon the T and carrying a burner bowl, a float chamber mounted on the casting and communicating with the T, a float mounted in the float chamber and carrying a depending valve in position to engage the valve seat of the nipple, for regulating the flow of oil therethrough, and means establishing communication between the burner bowl and nipple.

2. In an oil control for heaters, the combination of a support, a nipple carried thereby and communicating with a source of oil supply, said nipple having a valve seat formed therein, a T carried by the nipple and communicating therewith through the valve seat, a casting supported upon said T and having an opening therethrough, a float chamber mounted on said casting, a float carried in said float chamber and carrying a depending valve stem extending through the opening in the casting and the T, and having a valve in the lower end thereof in position to engage the valve seat of the nipple for regulating the flow of oil to the T, a hollow bushing communicating with the T, a manually controlled valve for regulating said communication between the bushing and T, the casting having an oil chamber formed therein, a tube connecting the hollow bush-

ing with said oil chamber, and a burner bowl mounted upon the casting and communicating with the oil chamber formed therein.

5 3. In an oil control, the combination of a supporting structure, a chamber located thereabove and adapted to communicate with a source of fuel supply, a valve seat disposed beneath the chamber, a burner supported above the chamber and communicating therewith, a float chamber disposed over the first-mentioned chamber, and communicating therewith independent of the communication with the burner, said float chamber being located within the confines of said burner, a float in the float chamber, and a valve extending downwardly vertically from the float and cooperating with the valve seat for controlling the supply of fluid 20 to the chamber.

25 4. In an oil control, the combination of a member having a valve seat formed therein and communicating with a source of fuel supply, a chamber disposed above said valve seat, a casting mounted above the chamber and carrying a burner communicating with said chamber, a float chamber mounted on the casting and communicating with the first-mentioned chamber, and a float mounted 30 in the float chamber, and carrying a depending valve in position to engage the valve seat for regulating the flow of fuel therethrough.

In testimony whereof I affix my signature.

35 ROBERT T. WILLIAMS.
